PNEUMATIC THREAD EXTRACTOR FOR
LOOMS

George A. Buffington, Worcester, Mass., assignor
to Crompton & Knowles Loom Works, Worcester,
Mass., a corporation of Massachusetts

Original application October 31, 1938, Serial No.
237,833. Divided and this application March
23, 1939, Serial No. 263,718. Renewed April 9,
1940

8 Claims. (Cl. 139—256)

This is a division of my co-pending application filed October 31, 1938, Serial No. 237,833.

This invention relates to improvements in 5
thread extractors for looms and it is the chief
object of the invention to provide an improved
intake mouth for the tube which receives the
thread.

In co-pending application Serial No. 190,637
filed by Turner there is set forth a pneumatic
10 thread extractor having a thread tube with an
intake mouth to be depressed at the time of
transfer for engagement with the thread which
extends from the selvage to the outgoing bobbin.
The thread which extends from the shuttle box
15 to the extractor is drawn into the tube on trans-
ferring beats of the loom. At a subsequent beat
the temple cutter severs the thread at the selvage,
whereupon the thread is completely removed
from the race and may if desired be deposited
20 into a thread accumulator.

It has been found desirable to construct the
intake mouth in such a way that the air rushing
into the tube can engage all sides of the
thread and it is an important object of my pres-
25 ent invention to provide a construction for the
mouth which will require the thread to be dis-
posed in some intermediate part of the stream
of air passing into the tube. It is a further ob-
ject of my present invention to provide a mouth
30 construction which will trap the thread to pre-
vent its accidental removal from the tube.

In the aforesaid application there is shown a
strip of pile fabric extending below the path of
the shuttle and into which the tongue of the
35 extractor projects so that during rearward mo-
tion of the lay the thread will be supported on
the pile tufts at the point above the lowest part
of the tongue. In that application, however, the
tongue is flat so that the thread can lie along a
40 surface in such a position as to be entirely on one
side of the column of air rushing through the
tube. It is a further object of my present inven-
tion to provide the tongue with a rib which shall
be located partly at least below the top of the
45 pile tufts during the backward stroke of the
lay for the purpose of placing the thread in the
stream of air and keeping away from the flat
surface of the tongue.

It is another object of my invention to form
50 the tongue as a separate part of the tube and
having an upwardly extending lug to be fas-
tened to and extend into the lower part of the
tube. This lug or shank preferably has a con-
cave surface facing the thread so that the in-
55 rushing draft of air can pass behind as well as in

front of the thread. In this way the thread is
kept from extending along a flat surface which
might otherwise interfere with its movement into
the tube and its response to attractive force of
the draft.

The control for the tube together with its time
of operation and means for creating an inrush-
ing draft of air may be the same as that shown
in the aforesaid application and such parts only
of the disclosure of that application are set forth
herein as are needed to indicate the use and
location of my present invention. 5

With these and other objects in view which
will appear as the description proceeds, my in-
vention resides in the combination and arrange-
ment of parts hereinafter described and set forth. 15

In the accompanying drawing, wherein two
forms of the invention are shown,

Fig. 1 is a vertical section through part of a
loom equipped with a pneumatic thread ex- 20
tractor provided with my present invention.

Fig. 2 is an enlarged side elevation of the
lower part of the extractor tube viewed from
the center of the loom, showing the preferred
form of my invention. 25

Fig. 3 is a front elevation looking in the direc-
tion of arrow 3, Fig. 2.

Fig. 4 is a bottom plan looking in the direction
of arrow 4, Fig. 2.

Fig. 5 is a vertical section on line 5—5 of 30
Fig. 3.

Fig. 6 is a front elevation of the tongue unit
which is inserted into the bottom of the ex-
tractor tube.

Fig. 7 is a plan view of the structure shown in 35
Fig. 6, and

Fig. 8 is a perspective view of a modified form
of the invention.

Referring to the drawing, particularly Fig. 1,
I have shown a loom frame 10 having a breast
beam 11 carrying pivot 12 for a transfer arm 13. 40
The latter is normally raised but is depressed
by mechanism not shown herein but illustrated
for instance in the aforesaid application when a
transfer of a full bobbin is to be made from the
magazine not shown into the shuttle S. The lay
L is reciprocated horizontally by connectors one
of which is shown at 14. The transfer will ordi-
narily take place when the lay is at front center
position, or when the lay is moved to its closest 50
position with respect to the breast beam, and
immediately thereafter the lay starts its back-
ward motion in a left hand direction with re-
spect to Fig. 1. A rod 15 pivoted to the lay as
16 extends rearwardly to operate a vacuum 55

pump not shown but similar to that set forth in the aforesaid application. While my present invention may be used in connection with the device shown in that application for producing a vacuum, yet I do not wish to be limited to the use of my invention with such vacuum producing means.

A flexible preferably rubber tube 20 fits over the upper end of a hollow metallic tube 21 held by a set screw 22 in a vertically movable carrier head 23. The tube is vertically adjustable with respect to the head and is normally in a raised position so that all parts carried by the tube are above the path of the shuttle on non-transferring beats of the loom. The head 23 is mounted on the forward end of a rod 24 and carries a roll 25 to be engaged by a plate 26 fastened to the trans-ferrer arm 13. At the time of transfer the plate 26 descends with the trans-ferrer arm to engage the roll 25 and lower the head 23 from its normally raised position to the position shown in Fig. 1. Thereafter on the backward stroke of the lay mechanism not shown herein but fully set forth in the aforesaid application restores the head 23 to its normally raised position.

The matter thus far described of itself forms no part of my present invention and may be constructed as set forth in the Turner application already mentioned.

30 In carrying my present invention into effect I provide the lower end of the tube with a downwardly opening pair of notches 30 located behind the front wall of the tube so that a lip 31 of the latter extends below the top of the notches. The 35 lower end of tube 21 supports a thread engaging unit A having a shank or bearing 32 extending into the tube and held in place by a rivet or pin 33. The forward face 35 of the shank 32 is concave forwardly or to the right as viewed in Fig. 2. 40 Extending forwardly and downwardly from the shank 32 is a tongue 36 having an upper surface 37. Extending preferably centrally upwardly along the surface 37 is a rib 38 which rises above surface 37 and has an upper rounded edge 45 along which the thread slides with a minimum of resistance. The rib terminates in an upwardly projecting finger 40 which is located in front of the notches 30. The finger also projects upwardly behind the lip 31 and in front of a portion 50 of the concave surface 35.

50 As shown in Fig. 7 the shank 32 is formed as slightly more than half a cylinder to facilitate its retention in the tube while the pin 33 is being placed. While this is a useful incident to the 55 construction of my invention I do not wish to be limited to it. The lower end of the tube 21 has projecting forwardly therefrom a thin plate or wing 50 having a downwardly and rearwardly inclined thread guiding surface 51 which leads 60 to the notch designated at N, Fig. 2, toward which the thread will be directed by rearward motion of the lay.

As indicated in Fig. 1 and shown more particularly in Fig. 5 the lay has therein a cross slot 60 65 to receive a body of pile fabric 61 the tufts of which project upwardly to a point not higher than the race plate 62 of the lay. The rib is so proportioned that when the intake tube is in its lowest position the bottom of the tongue and also 70 a portion of the rib 38 will lie below the top 65 of the pile fabric. It is to be understood that the taut thread extends along the race plate and across the slot 60 to be supported by the upper 75 ends of the tufts of the fabric 61 and it is this relation which permits the tongue and also the

rib thereon to be disposed partly at least below and behind the weft thread designated at W.

In operation the tube will be depressed to the position shown in Fig. 1 on a transferring beat of the loom. The forward part of the tongue and 5 the lower part of the rib 38 being embedded in the pile fabric with the thread extending along the race plate at points somewhat in front of or to the right as viewed in Fig. 2, of the notch N. The thread is then cut in the shuttle box in any 10 approved manner as set forth in the aforesaid application when the lay is in forward position, after which the lay starts to move rearwardly and carries the thread supported by the shuttle race toward the notch N. At the same time a 15 rush of air is induced into the notch N and upwardly along the tube 21, the air passing into the notches 30 and along a path between the lip 31 and the finger 40. Continued rearward motion of the lay directs the thread upwardly along the 20 rib 38 until the thread comes within the zone of influence of the draft of air, whereupon the thread will slide up over the finger 40 and behind the latter into the notches 30 and to a point in front of the rear part of the concave surface 35. 25 It should be stated that the rib 38 extends rearwardly from the finger 40 to the concave surface 35 so that it is impossible at any time for the thread to fall along a flat surface because of its engagement with the rib and finger. 30

This placement of the thread behind the finger 40 occurs during the first part of the rearward motion of the lay and ordinarily before the shuttle leaves the shuttle box. The thread, although cut at the shuttle eye at the time of transfer, will 35 therefore be held sufficiently taut to be drawn to the position described and be in the zone of influence of the inrushing draft of air before the shuttle is picked to release the cut end of the thread from frictional holding between the front 40 wall of the shuttle and the shuttle binder not shown. When in this position it will be observed especially with reference to Fig. 2, that the thread extends along part of the rib 38 and may lie against the edges 10 which marks the forward 45 terminations of the concave surface 35. The column of air passes under the thread as well as in front of it and behind it. The thread is therefore suspended in the moving column of air and as soon as the end cut at the shuttle eye is released by the picking of the shuttle said end will be drawn into the tube and will remain there until the other end of the thread is cut at the selavage on some subsequent beat of the lay. When the latter condition occurs the whole of the 55 thread is drawn into the tube and may pass along the rubber conveyor 20 to some point sufficiently remote from the path of the shuttle to prevent the latter from drawing the thread into the warp shed. 60

The form of the invention thus far described makes use of a rib extending substantially to the lower end of the tongue. I do not wish to be limited to this construction, however, inasmuch as it is sufficient if the unit A be so constructed that the column of air which rushes into the tube 21 can act on all sides of the weft thread. This result can be achieved without the use of the rib as set forth in the modified form of the invention shown in Fig. 8 wherein the tongue 80 corresponding to the tongue 36 is provided with two spaced air grooves or recesses 81 between which lies a rib 82. The upper surface may be level with the surface of the tongue 80. In this modified form the rib 82 has the rear part thereof 70 75 80 85 90 95 98

curved upwardly as at 83 to form the finger 40 which will be substantially the same as the finger shown in the preferred form of the invention.

In the operation of this modification the air moving into the tube 21 rises from the air grooves 81 which lie under the thread and in doing so draws the thread in the tube. Although I have shown two of the grooves or recesses 81 yet it is obvious that a single recess can be used inasmuch as such a construction would permit the thread to extend across a depressed part of the tongue. In other respects, such as the construction of the shank of the concave face and the disposition of the finger 40 and that portion of the rib lying behind it, the construction shown in Fig. 8 may be the same as that in the preferred form.

From the foregoing it will be seen that I have provided an improved intake for a pneumatic thread extractor wherein the unit located at the bottom of the tube 21 is so constructed that air moving into the tube can rise from a point below the thread, this condition being true whether the rib 38 of the preferred form of the invention be used or whether the tongue 80 is provided with one or more air recesses 81 as in the modified form. It will also be seen that the tongue 40 is so placed with respect to the lip 31 as to provide an effective trap for the thread to prevent the latter from escaping from the notches 30. Also, the forward face of the shank 32 is made concave for the purpose of permitting a part of the column of air which rushes into the tube 21 to pass behind the notches 30 and the thread located therein. Fig. 2 shows that the rear edge 75 of the notches 30 extend below the lowest part of the rib 38 defining the bottom of the thread pocket of which the notches 30 form the upper part, and it is this construction which maintains the thread out of contact with flat surfaces and in the path of the column of air rushing into the tube 21.

Having thus described my invention it will be seen that changes and modifications may be made therein by those skilled in the art without departing from the spirit and scope of the invention and I do not wish to be limited to the details herein disclosed, but what I claim is:

1. An attachment for the tube of a pneumatic thread extractor, said attachment comprising a downwardly and forwardly extending thread guiding tongue having thread engaging edges so located that a straight line passing from one of said edges to another edge will lie above a portion of the tongue to provide an air space below said line.

2. An attachment for the lower end of a tubular pneumatic thread extractor tube, said attachment having a downwardly and forwardly extending tongue with an upstanding rib terminating in a finger, the rib extending behind but at a level

lower than the top of the finger, and an attaching hub rigid with the tongue to be inserted into the tube, the hub being located behind the finger.

3. An attachment for the lower end of a tubular pneumatic thread extractor tube, said attachment having a downwardly and forwardly extending tongue with an upstanding rib terminating in a finger, the rib extending behind but at a level lower than the top of the finger, and an attaching hub rigid with the tongue to be inserted into the tube, the hub being located behind the finger and having a concave surface facing the finger.

4. An attachment for a pneumatic thread extractor for looms, said attachment comprising a tube the lower end of which is provided with an intake opening, a tongue extending forwardly and downwardly from the intake opening, and a thread hook projecting upwardly with respect to the tongue and toward the intake opening.

5. An attachment for a pneumatic thread extractor for a loom, said attachment comprising a tube the lower end of which is closed except for a thread intake opening, a thread guiding tongue projecting downwardly and forwardly from the intake opening and supported by the tube, and a thread hook having an upwardly opening throat directed toward the intake opening in the tube.

6. An attachment for a pneumatic thread extractor for a loom, said attachment comprising a tube the lower end of which is closed except for a thread intake opening, a thread guiding tongue supported by the tube and directed downwardly and forwardly from the intake opening in the tube, and a thread hook on the tongue having a thread receiving opening directed toward the intake opening of the tube.

7. An attachment for a pneumatic thread extractor for looms, said attachment comprising a tube the lower end of which is provided with an intake opening, a tongue extending forwardly and downwardly from the intake opening, a thread hook projecting upwardly with respect to the tongue and toward the intake opening, and a thread guard projecting forwardly from the intake opening to assist in directing the thread into said opening.

8. An attachment for a pneumatic thread extractor for looms, said attachment comprising a tube the lower end of which is provided with an intake opening, a tongue extending forwardly and downwardly from the intake opening, a thread hook projecting upwardly with respect to the tongue and toward the intake opening, and a thread guard located above and projecting forwardly from the intake opening end of the tube and assisting in directing a thread in front of the tube toward the intake opening and tongue.

GEORGE A. BUFFINGTON.
